UNITED STATES PATENT OFFICE.

EDWARD THOMPSON DIDEN, OF PRATTVILLE, ALABAMA, ASSIGNOR OF ONE-HALF TO
SAMUEL JOHN NUMMY, OF PRATTVILLE, ALABAMA.

PNEUMATIC CONVEYER.

1,082,113.

Specification of Letters Patent.

Patented Dec. 23, 1913.

Application filed May 5, 1913. Serial No. 765,620.

To all whom it may concern:

Be it known that I, EDWARD THOMPSON DIDEN, a citizen of the United States, residing at Prattville, in the county of Autauga and State of Alabama, have invented a new and useful Pneumatic Conveyer, of which the following is a specification.

This invention relates to improvements in elevators and conveyers and more particularly to that class of conveyers known as pneumatic conveyers.

An object of the present invention is to improve the construction of the conveyer whereby the tendency of material to clog therein will be largely eliminated, and furthermore to provide a conveyer which may be readily disassembled for the cleaning thereof.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated in which—

Figure 1 is a view in elevation of my improved conveyer attached to an air pressure fan and adapted to elevate and convey material from a bin. Fig. 2 is a similar view of a slightly modified form.

Referring to the drawings in which similar reference numerals designate corresponding parts throughout the several views, 1 is a pressure or blower fan for the supplying of air pressure. A bin or receptacle 3 illustrated in cross section is supposed to contain the material which is to be elevated and conveyed, the device in question being adapted to handle such material as cotton, wood pulp, wood shavings, etc.

An ejecting nozzle 4 comprising the outer conical casing 5 is connected to the fan or air blower 1 by means of the pipe 6. Extending within the conical casing 5 is the pipe 7 the same comprising the frusto-conical portion 8 through which extends the central aperture 9. The end of the pipe 7

extends within the bin or receptacle containing the material which is to be elevated and conveyed. The head 10 is provided with the annular flange 11, the same threadedly engaging the casing 5 as at 12. Said head 10 is provided with a central aperture extending therethrough and which threadedly engages the pipe 7 as at 12 and is adapted to abut against the shoulder 13 formed at the outer extremity of the frusto-conical portion 8. The manner in which the head is mounted allows the same to be readily removed, to thereby render accessible the portion of the ejecting nozzle lying between the outer surface of the portion 8 of the pipe and the inner surface of the casing 5. Also it will be readily appreciated that should the elevator and conveyer become clogged, by removing the head 10, a suitable bar or poker may be inserted therein and the same inserted within the cylindrical portion 14 of the delivery end of the nozzle to thereby effectually clean the said pipe. The ejecting nozzle renders it unnecessary that the raised and conveyed material pass through a fan and therefore the elevator and conveyer herein described is adapted to handle large material such as blocks of wood, wood shavings, and similar material. The detachable head 10 as explained, allows the ejecting nozzle to be readily opened for inspection and should the delivery portion 14 thereof become clogged, suitable steps may be taken whereby the same will be opened up. The air delivered by the fan 1 rushing through the casing 5 and around the portion 8 of the pipe 7 creates a suction therein which will effectually elevate material which may be disposed within the bin 3 and after the said material has passed the said nozzle the same will be conveyed by the pressure created by the fan 1.

The modified form as illustrated in Fig. 2 of the drawings illustrates the delivery portion 14' formed integral with the head 10' and connected to the pipe or injecting nozzle 7' by solder or other equivalent means as is the juncture between the pipe 6' and the pipe 14' effected.

Having thus fully described the invention, what I claim to be new and original with me is:—

1. An ejecting nozzle for a pneumatic conveyer comprising a casing including a cylindrical and frusto-conical portion, a de-

livery pipe connected to and leading from the restricted part of said frusto-conical portion, a head threadedly engaging the said casing, said head provided with an aperture 5 extending therethrough, and an ejecting nozzle extending through and engaging the head aperture, said ejecting nozzle being substantially frusto-conical and terminating adjacent the said delivery pipe, the removable head rendering the portion between the ejecting nozzle and casing accessible.

2. In a device of the class described, the combination of an outer conical casing, a pipe communicating with the side adjacent 10 the rear extremity thereof, a head provided

with a threaded annular flange adapted to engage the rear extremity of the said casing, said head provided with a threaded aperture extending centrally therethrough, and a pressure supply pipe extending through 20 said last mentioned aperture and provided with a shoulder adapted to abut the inner surface of said head.

In testimony that I claim the foregoing as my own, I have hereto affixed my signature in the presence of two witnesses.

EDWARD THOMPSON DIDEN.
